Application January 31, 1938, Serial No. 187,851

8 Claims. (Cl. 299—71)

This invention relates to lawn sprinklers of the type particularly adapted for sprinkling large areas, such, for example, as lawns of wide expanse, golf courses, gardens and more particularly orchards and fields.

An object of the invention is to provide a sprinkler of the type carrying a wheel adapted to be rotated by the discharge of water thereagainst and to itself break up and spray the water, and more particularly to provide means whereby the reversing action of the nozzle and associated parts may be accomplished in a substantially automatic manner so that an oscillatory action for the nozzle and associated parts may be obtained.

The present invention together with its objects and advantages will be best understood from a study of the following description taken in connection with the accompanying drawings wherein:

20 Figure 1 is a side elevational view of the improved sprinkler.

Figure 2 is a top plan view thereof.

Figure 3 is a detail sectional view taken substantially on the line 3—3 of Figure 1.

25 Figure 4 is a sectional view showing the mounting for the rotary disk or wheel.

Figure 5 is a longitudinal sectional view illustrating certain details hereinafter more fully referred to and with the gland nut removed.

30 Figure 6 is a fragmentary detail sectional view at the top end of the nozzle.

Referring to the drawings by reference numerals, it will be seen that this sprinkler comprises a tubular member 11 formed at one end as at 12 for threaded reception of a gland nut or base casting 12a which latter also serves to couple the member 11 with a suitable supply pipe.

Passing lengthwise through the tubular member 11 is a tube 13 one end of which extends into the end 12 of the tubular member 11 and is equipped with packing rings 14, retained by the nut 12a in a manner to provide in effect a packing gland for the exclusion of dust and dirt from the wearing part of the device.

45 The upper end of the tube 13 is externally threaded and screwed onto this end of the tube 13 as at 15 is one end of a nozzle 16.

The nozzle 16 at its free end is laterally enlarged as indicated generally at 17 and at said end has threaded into the main bore 18 thereof a suitable tip 19. In the enlarged end 17 of the nozzle 16 there is also provided a by-pass 20 of relatively small diameter into the outer end of 55 which is threaded a smaller tip 21 for a purpose

hereinafter made manifest. Rearwardly of the passage 20 the nozzle internally is suitably provided with a trash and dirt deflector 18a.

Adjacent the head 17 thereof the nozzle 16 on its underside is provided with an apertured boss 22 which receives one end of a shaft 23. The shaft 23 is held against axial movement through the opening in the boss 22 through the medium of a collar 24 fixed to the shaft 23 at one side of the boss and a nut 25 threaded on the end of the shaft at the side of the boss opposite to the collar 24 all of which is clearly shown in Figure 4.

Rotatably supported on the shaft 23 laterally of the nozzle 16 is a spray wheel or disk 26. The hub of the wheel 26 is confined on the shaft between the collar 24 and a bushing assembly shown in Figure 4 which includes a bushing cap 27 having an end fitting in a socket provided therefor in the adjacent end of the hub of the wheel 26, and a second end provided with a tapered socket 20 to receive the tapered end of a bushing member 28; and against the free end of which bushing member 28 is threaded home a retaining nut 29 on the shaft 23. The hub of the wheel 26 may be also provided with an oil hole 30 for lubricating purposes as shown in Figure 4.

On the side thereof facing the nozzle 16 the wheel 26 is provided with a circular series of short vanes or fins 31 that extend substantially 30 radial to the axis of the wheel. Also, integral with the wheel 26 at a suitable point in its periphery is provided a spoon 26a that, as shown is offset at an angle to the plane of the wheel and is provided on one face thereof with vanes 31a 35 constituting continuations of certain of the vanes 31 as best shown in Figure 1. In connection with the above it will also be noted that the by-pass tip 21 is at the side of the head nearest to the wheel 26.

Thus it will be seen that water issuing 40 from the nozzle 16 and striking against the vane equipped side of wheel 26 causes wheel 26 to rotate and the water from nozzle 19 striking weight or spoon 26a will impart a brief but powerful side drive to the sprinkler causing nozzle 16 45 and wheel 26 to swing as a unit in a lateral clockwise direction.

For changing the lateral direction of rotation of the nozzle 16 and wheel 26 as a unit so that the same will be caused to oscillate instead of 50 rotating in a continuous circle, there is carried on tubular member 11 Figures 5 and 3, adjustable cam clamping rings 33 and 35, the same being adjustable relative to each other and secured in adjusted position through the medium of these 55

clamps that embrace and are adapted to be tightened about the fixed tubular member 11.

The cam and clamping ring 33 is best described as an external cam, while the cam 36 on clamping ring 35 (Figure 5) may be described as an internal cam. It consists of an inwardly curving finger.

As shown in Figures 1 and 5 the cam 36 is disposed at a lower plane than the cam 33 so that 10 a tripping finger 37 hereinafter more fully referred to, is adapted to ride on the out-side-edge of the cam 33 and on the inside edge of cam finger 36.

The tripping finger 37 together with arm 32 is 15 formed integral with a hub, 39 fixed on one end of a stub shaft, 40 equipped on its free end with a nut 41 and journaled in a bearing boss 42 provided on the nozzle 16 in a manner as best shown in Figures 1 and 2.

20 A spoon or deflector 43 is adapted to move into and out of operative position relative to the tip 19 of the nozzle and is formed integral with a shank 44 that intermediate its ends is formed with a lateral shaft 45 journaled in a bearing boss 46 provided on the top side of the head 17 of nozzle 16 as shown in Figure 2. At its free end the shaft 45 is provided with a nut 46 as shown, to retain the shaft against axial movement through the bearing boss 46. Also, the 25 shank 44 adjacent the spoon 43 is provided with an angular projection 47 to which is connected one end of a spring 49 that is also connected to the free end of the arm 48 as shown in Figure 2. It will thus be seen that a swinging movement 30 of the arm 32 will be transmitted to the spoon 43 and the spring 49, when the spoon is passed dead center, will serve to yieldably retain the spoon in the position to which it has been moved.

35 Rotative movement of the lever 44 and spoon 43 in one direction is limited by a stop lug 50 formed on one side of the nozzle 16 while rotative movement of the lever or shank 44 in a reverse direction is limited by reason of a down turned end 44a provided on the lever 44 to engage a stop lug 51 provided on the nozzle 16 as best shown in Figure 2.

40 From the above description it will be apparent that the sprinkler operates in the following manner. Water issuing from the small jet 21 of the nozzle impinges on the vanes or fins 31 of wheel 26 causing the wheel 26 to revolve or spin about the shaft 23 as an axis, the said wheel rotating in a counterclockwise direction (see Figure 1). When the spoon 26a moves into the line of the 45 large jet of water issuing from the nozzle tip 19, the jet striking the vane equipped face of the spoon 26a as said spoon 26a passes through the jet of water, causes a brief but powerful side drive to be imparted to the sprinkler, thus causing the nozzle 16 and wheel 26 to swing laterally as a unit in a clockwise direction.

45 As the nozzle 16 and wheel 26 swing in the direction just mentioned, arm 37 moves into engagement with the cam 36 so that about the time the nozzle 16 and wheel 26 has reached the limit of its movement in a clockwise direction, the arm 32 is tripped for swinging the spoon 43 from the full line position shown in Figure 1 to the dotted line position shown in said figure thereby placing the spoon in the line of the jet of water issuing from the nozzle 19. Obviously, when the spoon 43 is moved into the dotted line position shown, the jet of water impinging thereagainst will cause a powerful lateral side drive to the sprinkler resulting in a reversing movement of the

5 nozzle 16 and wheel 26 as a unit. Thus the nozzle 16 and wheel 26 will be caused to swing laterally in a counterclockwise direction, a constant force being exerted by the water issuing from the nozzle 19 against the spoon 43.

5 As the nozzle 16 and associated parts now swing in this lateral counterclockwise direction, arm 37 will move out of engagement with the cam 36 and into engagement with the cam 33. This will result in a tipping of the arm 32 and 10 a consequent swinging movement of the spoon 43 back to the full line position shown in Figure 1, the spoon 43 being in this manner snapped out of line of the jet of water. Thus the parts are again in the position shown in Figure 1 to repeat 15 the cycle of operation just described.

20 In connection with the above it will be noted that wheel 26 continuously rotates in one direction during the entire operation of the sprinkler and that the wheel 26 and the nozzle 16 as a unit swing laterally first in one direction and then in a reverse direction to insure a thorough sprinkling of a large area of lawn, orchard, field or the like.

25 Having thus described the invention, what is claimed as new is:

1. A sprinkler of the character described which includes: a spray head having spray means to discharge two jets of water mounted to revolve on a substantially vertical axis; a vaned spray wheel rotatably mounted on said head and disposed in a substantially vertical plane laterally thereof, so that one of said jets of water issuing from said head will strike said vanes and cause rotation of said wheel; a spoon on said wheel offset at an angle to the plane thereof adapted upon rotation of said wheel to pass through the second of said jets of water issuing from said head to cause said head to rotate in one direction about its said vertical axis; a deflector spoon pivotally mounted on said head on the side thereof opposite to said wheel, said deflector spoon being adapted to swing into and out of the path of said second jet of water issuing from said head to cause said head to rotate in the opposite direction 45 when said deflector spoon is in said jet path; and cam means responsive to rotation of said head for actuating said deflector spoon.

2. A sprinkler of the character described which includes: a spray head, having a pair of nozzles 50 thereon, mounted to revolve on a substantially vertical axis; a vaned spray wheel rotatably mounted on said head and disposed in a substantially vertical plane laterally thereof, so that a jet of water from one of said nozzles will strike 55 said vanes and cause rotation of said wheel; and a spoon on said wheel offset at an angle to the plane thereof adapted upon rotation of said wheel to pass through a jet of water issuing from the other of said nozzles to cause said head to rotate 60 in one direction about its said vertical axis.

3. A sprinkler as defined in claim 2 which is provided with a deflector spoon pivotally mounted on said spray head on an axis parallel to the plane of rotation of the head and transverse to 65 the longitudinal axis thereof and on the side of the jet opposite to said spray wheel, said spoon being adapted to swing into and out of the path of the jet issuing from said second nozzle to cause said head to rotate in the opposite direction when 70 said spoon is in said jet path.

4. A sprinkler as defined in claim 2 which is provided with a deflector spoon pivotally mounted on said spray head on an axis parallel to the plane of rotation of the head and transverse to 75

the longitudinal axis thereof and on the side of the jet opposite to said spray wheel, said spoon being adapted to swing into and out of the path of the jet issuing from said second nozzle to cause 5 said head to rotate in the opposite direction when said spoon is in said jet path, and cam means responsive to rotation of said head for actuating said deflector spoon.

5. A sprinkler of the character described which 10 includes: a spray head having spray means to discharge water therefrom and mounted to revolve on a substantially vertical axis; a vaned spray wheel rotatably mounted on said head and disposed in a substantially vertical plane laterally 15 thereof so that a portion of the water discharged from said head will strike said vanes and cause rotation of said wheel; and a spoon on said wheel offset at an angle to the plane thereof adapted upon rotation of said wheel to pass through another portion of the water discharged from said 20 head to cause said head to rotate about its vertical axis.

6. A sprinkler of the character described which 25 includes: a nozzle-equipped spray head mounted to revolve on a substantially vertical axis; a vaned spray wheel rotatably mounted on said head and disposed in a substantially vertical plane laterally thereof, so that a jet of water issuing from said head will strike said vanes and cause rotation of said wheel; and a deflector 30 spoon pivotally mounted on said spray head on an axis parallel to the plane of rotation of the head and transverse to the longitudinal axis thereof, and on the side of the jet opposite to said spray wheel, said deflector spoon being adapted to swing into and out of the path of a jet of water issuing from 35 said spray head to cause said head to rotate about its said vertical axis.

7. A sprinkler of the character described which 40 includes: a nozzle-equipped spray head mounted

to revolve on a substantially vertical axis; a vaned spray wheel rotatably mounted on said head and disposed in a substantially vertical plane laterally thereof, so that a jet of water issuing from said head will strike said vanes and cause rotation of said wheel; a deflector spoon pivotally mounted on said spray head on an axis parallel to the plane of rotation of the head and transverse to the longitudinal axis thereof, and on the side of the jet opposite to said spray wheel, said deflector spoon being adapted to swing into and out of the path of a jet of water issuing from said head to cause said head to rotate about its said vertical axis; and means responsive to rotation of said head for actuating said deflector spoon. 5

8. A sprinkler of the character described which includes: a nozzle-equipped spray head mounted to revolve on a substantially vertical axis; a vaned spray wheel rotatably mounted on said 10 head and disposed in a substantially vertical plane laterally thereof, so that a jet of water issuing from said head will strike said vanes and cause rotation of said wheel; a deflector spoon pivotally mounted on said spray head on an axis 15 parallel to the plane of rotation of the head and transverse to the longitudinal axis thereof, and on the side of the jet opposite to said spray wheel, said deflector spoon being adapted to swing into and out of the path of a jet of water issuing from 20 said spray head to cause said head to rotate about its said vertical axis; and means for actuating said deflector spoon, said means including a trip finger pivotally mounted on said spray head 25 and connected with said spoon, a cam engageable by said finger to cause said spoon to swing in one direction and a second cam engageable by said finger to cause said spoon to swing in the opposite direction. 30
